CLAIM

I claim the ornamental design for an electrical connector, as shown and described.

DESCRIPTION

FIG. 1 is a top plan view of an electrical connector, showing my new design;

FIG. 2 is a front elevational view thereof;

FIG. 3 is a rear elevational view thereof;

FIG. 4 is a bottom view thereof;

FIG. 5 is a right side elevational view thereof;

FIG. 6 is a left side elevational view thereof;

FIG. 7 is a left perspective view thereof; and,

FIG. 8 is a bottom right perspective view thereof.

The broken line portion of the figure drawings is included to show environmental structure that forms no part of the claimed design.
